Primary Examiner—Terry A. Wallace*Assistant Examiner*—Mitchell I. Siegel*Attorney, Agent, or Firm*—Howrey & Simon; C. Scott Talbot[57] **CLAIM**

The ornamental design for a support arch for a slide, as shown and described.

DESCRIPTION

FIG. 1 is a front elevational view of a support arch for a slide showing my new design;

FIG. 2 is a rear elevational view thereof;

FIG. 3 is a top plan view thereof;

FIG. 4 is a bottom plan view thereof;

FIG. 5 is a right side elevational view thereof; and,

FIG. 6 is a left side elevational view thereof.

The broken line disclosure is for illustrative purposes only and forms no part of the claimed design.
